H. M. AARONS.

WINDOW GUARD.

APPLICATION FILED FEB. 2, 1921.

1,387,958.

Patented Aug. 16, 1921.

Henry M. Aaron Inventor

By his Attorney
Maurice Block,

UNITED STATES PATENT OFFICE.

HENRY M. AARONS, OF NEW YORK, N. Y.

WINDOW-GUARD.

1,387,958.

Specification of Letters Patent. Patented Aug. 16, 1921.

Application filed February 2, 1921. Serial No. 441,874.

To all whom it may concern:

Be it known that I, HENRY M. AARONS, a citizen of the United States of America, residing at New York city, Bronx county, 5 State of New York, have invented certain new and useful Improvements in Window-Guards, of which the following is a full, clear, and exact description.

This invention relates to improvements 10 in window guards or devices arranged for attachment to a window casing to prevent a window cleaner from falling out of the window. My improved guard is arranged so that it can be attached to a window of any 15 width and also held in any position vertically of the window frame. My improved guard is arranged for attachment to a window casing without resorting to screws, bolts, etc. While my device is especially arranged 20 for window cleaning purposes, it may also be used as a guard to enable one to utilize the window sill for flowers, etc.

One of the advantages of my improved guard is that it is simple and effective and 25 cheaply manufactured, as it is designed to obviate the necessity of machining. The frame which forms part of the device will be preferably cast, a suitable clamping device being employed to enable it to be se- 30 curely affixed to a window frame. The clamping device, which I employ, is of simple construction, durable and easily manipulated.

Other features of my invention will be 35 hereinafter set forth.

I will now proceed to describe my invention in detail, the novel features of which I will finally claim, reference being had to the accompanying drawing, wherein:—

40 Figure 1 is a sectional plan view of a window frame, having my improved guard applied thereto;

Fig. 2 is an enlarged sectional view, the section being taken on a line 2—2 in Fig. 1;

45 Fig. 3 is an enlarged sectional detail view, the section being taken on a line 3—3 in Fig. 2;

Fig. 4 is an enlarged vertical sectional view, the section being taken on a line 4—4 50 in Fig. 1;

Fig. 5 is a sectional view, taken on a line 5—5 in Fig. 4; and

Fig. 6 is an enlarged detail view, in side elevation, of one of the members of the 55 clamping mechanism.

As herein embodied, my invention com-

prises frame-members 7 and 8 which are arranged for application to a window frame 9. In this instance, I have illustrated the frame members 7 and 8 as applied to the 60 guide members 10 for the window sash, which operate in the channels 11, an illustration of said sash being omitted, the channel 12 being for the other window sash, which is also not shown. Each frame 7 and 8 is 65 provided with jaw members 13 and 14 to receive a guide member 10. Each frame is also preferably provided with a third jaw member 15 to also engage said guide member 10 for a purpose to be set forth. Each 70 frame 7 and 8 is also provided with passages therethrough, indicated by 16, to receive rods or trusses 17. Each frame 7 and 8 is further provided with a guide-way 18 to 75 slidably receive a hollow block 19, engaged at one end by links 20, the opposite end of each of said links being in engagement with the rods or trusses 17. The blocks 19 are moved longitudinally of the guide-ways 18 in one direction, by nuts 21 engaging bolts 80 22 carried by the said blocks and passing through the end wall 23 of the guide-ways 18. The links 20, as well as bolts 22 pass through the blocks 19, which are hollow, being provided with an opening 24 there- 85 through. The end wall 23 of each guide-way 18 is provided with a recess or slot 25 to enable the bolts 22 and links 20 to be connected to the blocks 19 before being applied to the frames. In other words, after the 90 bolts 22 and links 20 are connected to blocks 19, the said blocks can be inserted into the guide-ways by being slipped in sidewise, as the bolts 22 will enter the slots 25 (see arrow 26, Fig. 3).

95 To attach the device to a window casing, the jaw members 13 and 14 of each frame 7 and 8 will be applied to the adjacent window guide member 10, rods 17 having first been slipped through the openings 16 at the outer 100 end of the frames. The rods 17 may be of any suitable material, such as wood or metal. When the rods are passed through the openings 16, they also will be passed through the links 20 (see Fig. 2), said links and 105 block 19, together with the bolts 22, having been previously applied to the frames 7 and 8. After frames 7 and 8 have been applied to the guide members 10, they will be forced against the same and the rods 17 caused to 110 be jammed against the frames 7 and 8, within the openings 16, by means of the bolts 22,

which are caused to draw the blocks 19 in a direction away from the rods 17, which action will tend to pull the links in a direction to tightly bind the rods 17 and frames together. After the rods are jammed, the frames will be held against movement in a direction that would cause them to become separated from the guide-members 10.

Under ordinary conditions, the frames 7 10 and 8 will rest upon the sill portion 27 of the window frame, but may be supported in an elevated position relative to the sill (see Fig. 2), by means of a locking mechanism, consisting of a cam 28 actuated by a lever 29 15 through the medium of a shaft 30, which carries the cam 28. The cam 28 will be supported within a pocket 31 formed in the third jaw-member 15 carried by each frame 7 and 8.

20 After the device has been elevated to the desired position, the handles 29 will be operated to rotate the cams to cause them to engage the guide members 10, whereupon the frames will be held. After the frames 25 have been locked in the elevated position, the wing nuts 21 will be manipulated to draw the rods 17 firmly against the frames 7 and 8.

It will be apparent that my improved device will provide means whereby a window sill will be rendered absolutely safe for a window cleaner, or for placing flower pots, etc. on said sill, as the rods 17 will form a guard or fence, so to speak, against which a 35 window cleaner can lean, or against which articles can be placed.

The cam 28 will be preferably provided

with a blade 30^a to dig into the guide member 10; hence I need not altogether depend upon the pressure of the cam to hold the 40 frames in place.

Having described my invention, what I claim is:—

1. In a window guard, a frame having jaws to engage a window casing, said frame 45 being provided with an opening, a rod engaging said opening, said frame being further provided with a guide way, a block 50 slideable in said guideway, means to actuate said block, and a link carried by the block arranged to engage the rod to force the rod 55 against the wall of the opening engaged thereby.

2. In a window guard, a frame, means carried thereby, to engage a window casing, a rod releasably supported by the frame, a link engaging said rod, and means carried by the frame to actuate the link to draw the rod firmly against said frame.

3. A window guard assembly, consisting 60 of a pair of frame members arranged to releasably engage a window casing, rods releasably engaging the frames, binding means 65 engaging the rods and located adjacent the frames, but not connected thereto, and means carried by each frame to actuate the adjacent binding means to lock the frames and rods firmly together.

Signed at New York city, N. Y., this 1st day of February, 1921.

HENRY M. AARONS.

Witnesses:

MAURICE BLOCK,
EDWARD A. JARVIS.
